(57) **CLAIM**

The ornamental design for a tire, as shown and described.

DESCRIPTION

FIG. 1 is a front view of a tire in accordance with our new design;

FIG. 2 is a perspective view thereof;

FIG. 3 is a side view thereof, the opposite side elevation view being identical thereto; and,

FIG. 4 is a partial front elevation view thereof, showing area 4 of FIG. 1 at an enlarged scale.

The broken lines depict environmental subject matter only and form no part of the claimed design.

1 Claim, 4 Drawing Sheets
